DELMAR D. DOOLEY, OF ROCK ISLAND, ILLINOIS, ASSIGNOR TO DEERE & MANSUR COMPANY, OF MOLINE, ILLINOIS, A CORPORATION OF ILLINOIS.

VALVE MECHANISM FOR PLANTERS.

1,215,628.

Specification of Letters Patent. **Patented Feb. 13, 1917.**

Application filed July 3, 1914. Serial No. 848,906.

To all whom it may concern:

Be it known that I, DELMAR D. DOOLEY, a citizen of the United States, residing at Rock Island, in the county of Rock Island and State of Illinois, have invented certain new and useful Improvements in Valve Mechanisms for Planters, of which the following is a specification, reference being had therein to the accompanying drawing.

10 This invention relates to improvements in planting mechanisms, particularly to improvements in the valve mechanisms or devices which arrest, accumulate, and finally deliver the kernels or seeds to the ground.

15 Figure 1 is a vertical section showing the initial seed-delivering mechanism, proper, together with the shank, or boot, and the valve mechanism of a planter embodying my improvements.

20 Fig. 2 is a section showing the parts of the valve mechanism when they are thrown to their extreme position for drilling;

Fig. 3 is a view showing the parts of the valve mechanism at the time when a hill of kernels is completed in the upper part of the chuteway and the previous hill of kernels is in position on the lowermost resting place;

Figs. 4 and 5 are perspectives of valve
so parts detached.

As before stated, the present invention relates more particularly to matters incident to the construction and mode of operation of the valves in planters. As they can be used in connection with such other parts of planting mechanisms as are found in either of many styles of machines, it is not necessary to here give full illustration or description of the latter. However, enough of a planting mechanism is conventionally or diagrammatically illustrated to indicate the relationships of the valve mechanism to the various parts of the entirety.

As concerns the other elements, suffice it to say, that A indicates the front frame, or runner frame, B, the bars of the rear frame, which at their front ends are hinged to the former, and are carried by the axle D, the latter, in turn, resting upon the covering ground wheels C. The front frame carries seeding mechanisms for two rows of plants, together with chutes or down guides for the seed, and the furrow-opening runners. Power is taken from the ground wheels and axle, as by sprockets at P and G, through

chain F, to the seeder shaft L, which by gearing at M and N, imparts intermitting rotary movements to the seed-delivering devices, the shaft L being connected to the shaft I by gearing at J and a clutch at H. 60 The tappet wire, commonly used with the machine, engages with forks on the check heads E, which impart reciprocatory rocking movements to the shaft E', the latter being adapted to open and close the valves below the seeding mechanism, and also to close the parts of the clutch at H. 65

As above indicated, the details of the different sets of parts referred to do not, as details, enter into the construction of the valve mechanism. But they should be had in mind as correlated therewith in attaining the purposes of the present invention. 70

1 indicates the front part of the shank or boot which is interposed between the runner and the front frame. Within it is the approximately vertical passageway through which the seeds pass downward, partly formed by the rear wall 3 and partly by a partition or diaphragm at 2. This shank or boot also carries the movable parts of the valve mechanism. At its upper end there is a casting indicated by 4, upon which rests the stationary bottom element 5, that supports the seed receptacle O and the movable parts of the seed-delivering devices, including gear ring 7 and the seeding plates at 8, together with the cut-off and knocker devices; all of which latter, also, may be of any preferred form.

The seed-delivering devices are intermittently actuated, and at each actuation receive some of the seeds in series and deliver them, *seriatim*, to the orifice or throat at 6.

There are three valves or seed-arresting devices in this mechanism, they being indicated by 10, 11 and 12. Above these respectively are the chambers 13, 14 and 15. There are but two main valve parts which are movable, one at the upper end of the shank and the other at the lower. The movable element at the upper end comprises the vertical or approximately vertical walls 19, 20, 21, 22 and 23. These wall sections are preferably cast integral with a vertical face plate 24, from which they project inward. The arresting plates or valves 10 and 11 are preferably cast integral with the companion face plate 25 oppositely arranged to that of 24, and held stationarily in the upper end of the 110

shank and in its interior chamber. The face plates 24 and 25 are pivotally connected together at 26. The rock shaft E' has a crank arm 27 which, through a link 28, is connected 5 to the swinging valve casting by a pivot 29.

When a tappet strikes a fork or either of the check heads E, the rock shaft E' throws the arm 27 downward, which results in pulling the upper swinging valve element 10 (plate 24 and its attachments) from the position shown in Fig. 1 toward that shown in Fig. 2. The spring connected with the rock shaft and the tappet fork returns the shaft to normal position and swings the 15 plate 24 and the parts carried thereby back to the position shown in Fig. 4. During these movements a hill of seed, say three corn kernels, is carried from one position to another at the upper end of the boot, and 20 is finally delivered over the plate section 11^a into the main vertical chuteway 30, through which it passes to the lower valve. At 25 12 there is an inclined surface formed on the metal of the shank upon which the seeds of a hill can temporarily rest. 16 is a box-like casting which coöperates with the wall 12 to temporarily hold the kernels. 31 is a movable wall piece adapted to close and 30 open the end of the box-like structure 16. It is pivoted at 18 to the stationary part of the shank. It is formed with a finger or arm 32 positioned to have a slot or elongated opening between it and the plate 31. 33 is a finger or cross pin carried by the valve part 16 35 and positioned in this slot. 16' is a rod extending from the valve box 16 up to the pivot at 14. When the rock shaft E' is moved by a tappet, it pushes downward on the rod 16' and the valve box 16, and 40 the latter, in turn, through the pin 33, pushes backward the closing plate 31.

The diaphragm or wall 2 in the shank is positioned in relation to the front wall 1 in such way as to leave a substantially 45 enclosed chamber for holding and protecting the valve rod 16'. Fig. 4 illustrates the parts in their normal positions; the chute section 6 is open, that at 13 is closed against the passage of seed therefrom, and that at 50 14 against the entrance of seed.

The operations of the parts that have been described will be readily understood upon examination of the drawings. Assuming the parts to be in the positions in Fig. 2, 55 and that a check row wire is in position across the field and on one of the heads E, when a tappet impinges on the fork, the latter gives a rocking movement to shaft E'; the arm 27 swings downward; it simultaneously pushes downward on the lower valve box 16 and pulls forward the upper 60 rocking valve plate 24. The downward movement of the valve box 16 opens the foot of the passageway, permits the three 65 kernels of the hill on wall 12 to drop (or

positively pushes them) downward and backward. At the same time, at the upper end of the valve apparatus, the walls 21 and 20 are moving forward, the former opening the passageway into the valve pocket at 14, 70 and the latter (20) pushing the accumulated kernels from the valve plate 10 off therefrom and dropping them onto the valve plate 11. They are held on this plate 11 by the vertical wall sections at 21, 22, the 75 lower edge of the latter moving close to the upper surface of the plate 11. These actions occur during the time (an eighth of a second or thereabouts) that the wire tappet is positively engaging with the fork. 80

Then, after the tappet escapes from the fork, the spring at 34 returns the latter, the rock shaft, and the parts connected thereto, to the positions shown in Fig. 4, that is, to their initial positions. This results in instantly drawing up the valve box 16 and the closing plate 31, and then results in causing the plate section at 22 (in the backward swing of the upper valve plate) to push the kernels received during the first stroke of the fork on the valve plate 11, up to the top of that plate, whereupon they slide over the part 11^a, drop through the boot passage 30, and are caught by the parts 12, 16 and 31. 90

As soon as these movements of the valve parts have been completed and the fork is returned, the throatway at 6 again registers with the chamber at 13 and the parts are ready to receive the first kernel of the next 100 series of three to drop from the seed plate, all of the series being caught upon and held by the stationary valve plate 10. After that the parts are ready for the next valve throw caused by the action of the next tappet on the wire. 105

The various parts of the machine are so related to each other and to the distances between the tappets on the wire, that the planting cycle (including the entire movement of the seed plate, and the entire movement of the valve element) shall commence and stop in an interval of time much shorter than that occupied by the travel of the machine from hill to hill, that is, from tappet to tappet. If the hills are planted 42 inches apart, the plate and valve cycle will be equal to only 28 inches, or thereabouts, of the travel from hill to hill. Consequently, 110 there is ample time to provide for corrections of any errors that might result from the departure from the theoretically correct peripheral travel of the wheels C, which travel governs the movements of the seed plate, irrespective of the travel of the valve parts. The valve pocket at 14 above plate 10 can, with assurance, be held closed long enough to receive the third kernel of the 115 next hill, even though the seed plate should, because of irregularities of movement of 120 125 130

the ground wheels, not stop its rotary movements at the theoretically correct instant.

By providing two resting places for the kernels, at horizontal planes, which are close together, and are both close to the seed plate or dropping mechanism, I overcome the serious difficulties that have been met with in single-kernel-drop planters that have been heretofore made, and which 10 have been incident to the fact that the time between the closing of the lower valve and the final release of the kernels from their last support above the lower valve has been so short that there would be leakage of 15 hills or kernels, or breaking of the kernels because of being caught by the lower valve parts just as they were closing. The accumulation of the kernels of the hill (as they drop from the seed-delivering mechanism) upon a valve plate such as that at 20 10, and then, before finally dropping them, catching them on an intermediate valve device, as at 11 (which is remote from the lower valve, and whose presence gives assurance that the kernels will be arrested 25 before finally dropping toward that valve) increase the accuracy in the planting.

The wall plate 23 on valve plate 24, although it moves with that plate, is always 30 in a position such as to serve as a guide for the kernels and lead them with precision into the main down chute or passageway 30.

If "hills" containing three kernels each 35 are taken by the seeder plate from the mass in the seed holder and delivered through the passageway to the ground a plate with predetermined arrangement of cells is used; and in case the "hills" are to contain four 40 kernels, each, a plate of another conformation is employed. I use the term "hill" for brevity to indicate the set of kernels which are passed together downward through the mechanism to be deposited at one point in 45 the ground.

From the above description it will be seen that each hill of kernels is at each successive stage of advance received upon a stationary supporting plate or surface, and that those of each "hill" are, at the successive actuations of the operating mechanism, 50 positively engaged by a pushing device which carries them to a horizontal line, over which they are all dropped simultaneously.

When it is desired to use the planter 55 for drilling (in contradistinction from hill-dropping) it is only necessary to turn the rock shaft back to the rearmost position 60 which it reaches when drawn by the tappet in hill-dropping and fasten it in that position in any of the well known ways. Such movement of the rock shaft throws the crank arm 27, the link 28 and the valve 65 plate 24 with its cross wall sections 19, 21 and 22 to their extreme outer position, and

at the same time the lower valve rod 15 and valve box 16 are pushed down and all are fastened in their open position. This results in providing and maintaining an open passageway from the initial throat 6 70 through the main duct 30, to the ground. The wall 19 on the valve plate 24 is now positioned and held in front of the throat 6, there being a slot at 35 to receive the edge of the stationary valve plate 10. 75

What I claim is:

1. In a planting mechanism, the combination of a boot having an approximately vertical chuteway or guide, a valve at the lower end of said guide near the ground, a seed holder above the boot, a rotary plate for intermittently withdrawing seed from said holder, a short chute immediately below the plate to receive "hills" of seed therefrom, a chamber immediately below the short chute 80 having a stationary bottom 10 and a cut-off 9, a second chamber situated in vertical lines remote from those of the main chuteway, and having a stationary bottom 11 inclined away from said chuteway, and vibrating 85 devices for positively advancing the hill of seeds from the first stationary bottom to the second, and then positively advancing them 90 upward on the second stationary bottom to the main chuteway, and adapted to deliver 95 them to the chuteway at points in unobstructed paths on vertical lines to said bottom valve.

2. In a planting mechanism, the combination of an initial intermittently acting seed 100 delivering device, a chuteway or guide, a valve at the lower end of said chuteway near the ground, two successively acting seed arresting devices in different horizontal planes but relatively close together and close to the 105 initial seed delivering devices, the second seed arresting device having a stationary bottom inclined away from the chuteway and means positively engaging with the seeds for pushing them off from the said 110 arresting devices at each actuation of the seed delivering device, the lower of the said two arresting devices holding the seed until the lower valve is closed. 115

3. In a planting mechanism, the combination of an initial intermittently acting seed delivering device, a passageway for the seeds delivered thereby having a short upper section immediately below the seed delivering device, a second section which is 120 relatively short and normally closed against the passage of seed, a third section which is relatively short and normally closed to the entrance of seed, and a fourth section which is relatively long, a valve at the bottom of 125 the fourth section, and means adapted to positively engage with the seeds at the lower ends of each of said sections of the passageway and push those from the second section to the third, those from the third sec- 130

tion to the fourth, and those in the fourth section to the ground.

4. The combination with a seed delivering device, of a down passage in four sections, 5 means for delivering a plurality of seeds to the first section, means for positively engaging with the seeds in the three lower sections and forcing them from the second section to the third, from the third section 10 to the fourth, and from the fourth section to the ground during each actuation of the

seeding mechanism, and means for preventing the passage of seeds from the first to the second section during the time of the aforesaid delivery from the second section to the 15 third and from the third to the fourth.

In testimony whereof, I affix my signature, in presence of two witnesses.

DELMAR D. DOOLEY.
